STITCHING MACHINE

Joseph William Bedard, Hoosick Falls, N. Y.

Application September 26, 1935, Serial No. 42,170

26 Claims. (Cl. 112—219)

This invention relates to means for automatically stopping a rotating shaft, such as the main drive shaft of a stitching machine, and more particularly to means for automatically stopping the main drive shaft of such machines at a desired final position.

In the operation of such machines it is generally necessary that the last stitch at the end of a run be completed before the work can be removed from the machine, or before the work can be turned to start a new run. Heretofore, many attempts have been made to provide such machines with braking mechanisms which would stop the machine when the last stitch in a run was completed, but all such mechanisms have been quick acting, with the result that machines equipped with such mechanisms necessarily had to be run at low speeds to avoid damage to the delicately constructed parts. In consequence, the original method of hand stoppage is still practiced to a considerable extent, this consisting in placing the hand upon the shaft hand wheel, bringing the same to a stop, and then turning or advancing the wheel until the shaft is in the desired final position.

In accordance with the present invention, means are provided for rotating the shaft at a high rate of speed, and for bringing it to a dead stop without strain on the delicately constructed parts associated therewith when it has been rotated to a final desired position, and to this end, the shaft is rotated at the beginning of a run at a high rate of speed by a primary source of power, and then as the end of the run is neared at a slower rate of speed by an auxiliary source of power, which operates against a braking force until the shaft has been rotated to a final desired position, at which time the auxiliary source of power is automatically rendered inoperative and a main brake is rendered operative to bring the shaft to a dead stop in this position.

For a clear understanding of the invention, reference may be made to the accompanying drawings. In these drawings, however, the invention is shown merely in preferred form and by way of example, but obviously many changes and variations may be made therein and in its mode of operation which will still be comprised within its spirit, and it is to be understood that the invention is not limited to any specific form or embodiment, except in so far as such limitations are specified in the claims.

Referring to the drawings:

Fig. 1 is a perspective view of a stitching machine embodying the features of the present in-

vention, and having portions of the top of the bench or table upon which the machine is mounted broken away to more clearly show the relation of parts;

Fig. 2 is an end view, partially in section;

Figs. 3, 4 and 5 are detail views which show various positions of the means employed in locking the auxiliary source of power in operative position;

Fig. 6 is a detail view, in section, showing the ratchet disks and the clutch cones in their normal position wherein the inclined teeth on the oppositely disposed ratchet disks are in full engagement and the clutch cones are disengaged;

Fig. 7 is a detail view, in section, showing the inclined teeth on the oppositely disposed ratchet disks partially disengaged and the clutch cones engaged;

Fig. 8 is a perspective view, partially in section, of the knee treadle shaft, the knee treadle and the operating mechanism connected therewith;

Figs. 9 and 10 are diagrammatic views illustrating the various steps of the mechanism shown in Fig. 8;

Fig. 11 is a rear view, having portions broken away to more clearly show the relation of the various parts;

Figs. 12, 13 and 14 are detail views, partially in section, showing various positions of the mechanism employed in applying a main brake on the main drive shaft and in rendering the auxiliary source of power inoperative; and

Fig. 15 is an enlarged detail view of a portion of the mechanism employed in locking the auxiliary source of power in operative position, in applying a main brake on the main drive shaft and in rendering the auxiliary source of power inoperative.

As shown, 20 is a bench or table upon which is mounted a stitching machine 21. As usual, the machine is equipped with a needle 22, a presser foot 23, and a feed pawl (not shown) which cooperates with the presser foot 23 to advance work under the needle. The presser foot 23, as usual, is rendered operative or inoperative by a rocker arm 25 pivotally mounted on a stud 26 carried by the main frame of the machine, and the needle 22 and the feed pawl are operated in a manner well understood in the art from the main drive shaft 27 of the machine.

In accordance with the present invention, means are provided for rotating the main drive shaft 27 at a high rate of speed at the beginning of a run, and in the present embodiment of the invention, this is accomplished by removing the

usual main drive shaft hand wheel, and extending the shaft, as by screwing a stud 28 into a tapped opening formed in the end thereof, as shown more clearly in Fig. 6. A face cam disk 5 having an extended bearing bushing 31 is so mounted on the extended shaft as to rotate in unison therewith, and at its outer end the bushing 31 is reduced to provide a seat for a primary power pulley 32, which is fixedly mounted thereon. The primary power pulley 32 is connected by a belt 33 to a primary power drive pulley 34 fixedly mounted on a sleeve member 35 which comprises the driven member of a power transmission clutch 35. The sleeve member 35 is rotatably mounted on a shaft 37 which comprises the driving member of the clutch 36, and during the normal operation of the machine the shaft 37 is rotated continuously from any suitable source of power, such as an electric motor (not shown). The driven member of the clutch 36 is connected by an adjustable rod 38 to a foot treadle 39, which, when elevated, maintains the driving and driven members of the clutch 36 out of engagement, and which, when depressed, maintains the driving and driven members of the clutch in engagement, at which time the primary source of power is rendered operative, and the main drive shaft 27 is rotated thereby at a high rate of speed.

In further accordance with the present invention, means are provided for continuing the rotation of the shaft 27 at a slower rate of speed by an auxiliary source of power after the clutch 36 has been disengaged and the primary source of power rendered inoperative, and to this end an auxiliary power pulley 41 is rotatably mounted on the bearing bushing 31, and it is connected by a belt 42 to a pulley 43 mounted on a shaft 44 which is positioned parallel to the shaft 37 on which the primary power drive pulley 34 is mounted. A small drive gear 45, mounted on the shaft 37, engages a larger gear 46 mounted on the shaft 44, with the result that the auxiliary power pulley 41 idles about the bearing bushing 31 until the auxiliary source of power is rendered operative. The auxiliary source of power is adapted and arranged to rotate the main drive shaft 27 at a much slower rate of speed than the primary source of power, so that when it is first engaged it, in effect, serves as a brake to slow down the speed of rotation of the shaft 27.

In accordance with the present embodiment of the invention, means are provided for rendering the auxiliary source of power operative in response to the movement of a treadle operable by the knee of the operator, so that the hands of the operator are always left free to guide and manipulate the work under the needle. To this end the auxiliary power pulley 41, which is rotatably mounted on the bearing bushing 31, is provided with a driving male clutch cone 47 and the cam disk 39 which rotates in unison with the main drive shaft 27 is provided with a driven female clutch cone 48. Two ratchet disks 53 and 54 are loosely mounted on the bearing bushing 31 between the rotatably mounted auxiliary power pulley 41 and the primary power pulley 32, which is fixedly mounted on the bearing bushing 31. The adjacent faces of these ratchet disks are provided with a number of engaging teeth having inclined faces. The outer ratchet disk 54 is maintained stationary at all times by means of a bracket 58 secured at its lower end on a stud 57 carried by the main frame 76 of the machine and at its upper end on the bear-

ing bushing 31 adjacent the inner face of the primary power pulley 32. The inner ratchet disk 53, however, is secured to an offset lever 59 at the forward end thereof, and a tension spring 61 tends to rotate the lever and the inner ratchet disk 53 clockwise, as shown in Fig. 1, with the result that the inclined teeth on the ratchet disks 53 and 54 are normally maintained in full engagement, and when this condition obtains a compression spring 49 interposed between the auxiliary power pulley 41 and the cam disk 29 acts to maintain the clutch cones 47, 48 disengaged.

The offset lever 59 at its inner end is provided with a segment 62 having a number of horizontal teeth which are adapted and arranged to engage a pawl 64 pivotally mounted on the side of a main bracket 65 secured to the main frame of the machine, as by a plurality of bolts 66. The pawl 64 is normally maintained in the path traveled by the segment 62 by means of a hairpin spring 67. The offset portion of the lever 59 is positioned above a roller 68 mounted on a vertically disposed rod 70 at the upper end thereof. The rod 70, at its central portion, is journaled in a bushing 71 carried by an extension 72 secured to the main bracket 65 and, as shown more fully in Figs. 3, 4 and 5, it is provided with a stud 73, which normally rests in the bottom of a vertical slot 74 in the bushing 71 to support the roller 68 beneath the offset portion of the lever 59. The lower end of the rod 70 is disposed within a compression spring 75, the upper end of which bears against a collar 76 carried by the rod 70, and the lower end of which rests on recessed plate 77 which, in turn, normally rests on a bearing bushing 78 positioned in the top of the table 10. The recessed plate 77 is secured to the upper end of a rod 79 journaled in the bearing bushing 78, and the lower end of the rod 79 terminates above a spring pressed latch 80, which is so mounted on the outer end of a rod 81 that it is capable of being folded upwardly when it is subjected to a force applied from beneath, and of being instantly returned to its normal straight position when the force is released. The rod 81 at its inner end is adjustably secured, to a block 85 which is fixedly mounted on a treadle shaft 86 journaled in bearings 87 secured to the underneath side of the top of the table 10. The treadle shaft 86 is also provided with another block 88 to which the upper end of a connecting rod 89 is secured. At its lower end the connecting rod 89 is adjustably secured to a vertically disposed knee treadle 93 which, when moved to the right against the action of a full spring 94 acts through the above described mechanism in a manner which will subsequently be set forth to force the clutch cones 47, 48 into frictional engagement and so render the auxiliary source of power operative.

In further accordance with the present invention, means are provided for applying an additional braking action on the main drive shaft 27 while it is being rotated by the auxiliary source of power, and for applying a main brake on the main drive shaft 27 and for automatically rendering the auxiliary source of power inoperative after the shaft 27 has been rotated thereby to a final desired position where, for example, the needle is raised and a stitch is fully completed.

To these ends the face cam disk 29, as shown in Figs. 12 to 14 inclusive, is provided with a cen-

trally disposed cam 97, having a single high segment 98, and with a concentric cam segment 99. The distance from the axis of rotation of the face cam disk 29 to the peak of the high segment 98 on the centrally disposed cam 97 and to the outer edge of the concentric cam segment 99 is the same; and at one end the concentric cam segment 99 is provided with a cam latch 101, which normally forms a continuation from this end of the concentric cam segment 99 around to the peak of the high segment 98 on the centrally disposed cam 97. The cam latch 101 is pivotally secured to the end of the concentric cam segment 99, and it is maintained in its normal bridged position by means of a hairpin spring 99a. The width of the concentric cam segment 99 is such as to provide a cam race 103 which is adapted and arranged to receive a stud 105, carried by the upper end of a main rocker arm 106. At its lower end the main rocker arm 106 is pivotally mounted on the stud 57 which, as stated heretofore, is carried by the main frame of the machine, and a tension spring 108, and a leaf spring 109 tend to rotate the rocker arm 106 counter-clockwise, as viewed in the drawings. At one end the tension spring 108, as shown more clearly in Fig. 2, is connected to the rocker arm 106 and the other end thereof is secured, as by a wing nut 111, to a bracket 112 carried by the main frame of the machine. At its lower end the leaf spring 109 is positioned in a slot cut in the main bracket 65, and the upper end thereof is maintained pressed against the rocker arm 106 by an adjusting screw 114 threaded through a boss 115 on the main bracket 65. Normally, the main rocker arm 106 is locked back against the action of the springs 108 and 109, and it is so positioned that the outer surface of the concentric cam segment 99, the cam latch and the peak of the high segment 98 pass immediately in front of the stud 105, as the face cam disk 29 rotates during the normal operation of the machine, this being accomplished by a latch lever 116 which engages a latch block 117 carried by the main rocker arm 106. The latch lever 116 is pivotally mounted on a stud 118 carried by the main bracket 65, and normally it is maintained in its latched position by a compression spring 119 positioned between a rear shoulder on the latch and a boss 123 carried by the main bracket 65, and to limit the rotation of the latch lever 116 about its pivotal connection under the influence of the compression spring 119, the rear end thereof is adapted and arranged to engage the boss 115 when it is in its latched position, this arrangement being provided to permit the latch to fold upwardly when a force is applied thereto from underneath, and to return to its latched position when the force is removed. A trip latch 124 is positioned beneath the latch lever 116 for unlocking the same. This trip latch 124 is carried by an L-shaped rocker arm 125, and it is so secured to one thereof that it is capable of being folded upwardly when a force is applied from beneath, and of being restored to its normal latched position when the force is removed. The L-shaped rocker arm 125 is pivotally mounted on a stud 126 carried by the main bracket 65, and at its other end it is provided with a guide stud 131 positioned in a vertical slot 132 formed in a connecting link 133, this arrangement being provided to permit a limited amount of free or lost motion between the end of the L-shaped lever 125 and the connecting link 133; and to adjust or limit the amount of such free or lost motion of the connecting link 133 is provided with an adjusting screw 134 which protrudes into the slot 132 at the upper end thereof. The connecting link 133, at its lower end, is connected to a rod 135 which extends downwardly through an opening 136 in the top of the table 10, and which is pivotally connected at its lower end to the inner end of a rod 137. At its outer end the rod 137 is adjustably secured to a block 138 fixedly mounted on the treadle shaft 86 to which the knee treadle 93 is operatively connected. A brake carrying rocker arm 141 is pivotally mounted on a stud 142 carried by the main rocker arm 106, and at its forward end this brake carrying rocker arm is provided with a stud 140 on which a brake shoe 143 is pivotally mounted. The brake shoe 143 is adapted and arranged to frictionally engage the periphery of the face cam disk 29 when the brake carrying rocker arm 141 is rotated clockwise, as viewed in the drawings. The brake carrying rocker arm 141 is so mounted on the main rocker arm 106 that the brake shoe 143 is forward of a vertical center line through the axis of rotation of the main drive shaft 27, and the distance from the pivotal stud 142 to the end of the brake carrying rocker arm 141 on which the brake shoe 143 is mounted, is considerably shorter than the distance from the pivotal stud to the rear end thereof so that when a slight downward thrust is exerted on the rear end of the brake carrying rocker arm 141, the brake shoe 143 is forced into firm frictional engagement with the periphery of the face cam disk 29. As shown more clearly in Figs. 1 and 14, the brake carrying rocker arm 141 at its rear end is provided with an angularly disposed slot 144 within which a stud 145 carried by the rear end of a release rocker arm 146 is positioned. The release rocker arm 146 is pivotally mounted on a stud 147 carried by the main bracket 65, and at its forward end it is pivotally secured to a vertically disposed connecting rod 148 at the lower end thereof. The connecting rod 148 at its upper end is pivotally mounted on a trunnion 149 which extends outwardly from a plunger 151 through a vertical slot 152 formed in one side of a housing 153 which comprises a portion of the main bracket 65. The lower end of the plunger 151 is journaled in a vertically disposed cylinder 154 formed within the housing 153. The other side of the plunger 151 is provided with a trunnion 155 which also extends outwardly through a vertical slot 156 formed in the other side of the housing 153, and this trunnion 155 is positioned beneath the latch 146 which serves to maintain the auxiliary source of power locked in operative position. Normally the plunger 151 is maintained downwardly in the cylinder 154 against the action of a compression spring 157 by means of a parrot lever 158. The parrot lever 158 is pivotally mounted on a stud 159 carried by the main bracket 65 and the beak of the lever is normally maintained over the top of the plunger 151 by means of a hairpin spring 163. At its lower end the parrot lever 158 is recessed to form a shoulder 164, and the free end of a lever 165 pivotally mounted on the main rocker arm 106 is normally maintained in interlocking engagement therewith by means of a leaf spring 166 which is so pinned to the main rocker arm 106 as to constantly urge the lever 165 upwardly. At its outer end the lever 165 is provided with a downwardly curved guide lip 167 which is adapted and arranged to engage the tapered face of a guide block 168 carried by the 75

main bracket 65 as the main rocker arm 106 is rotated clockwise as viewed in Fig. 14.

In operation, and at the beginning of a run, the primary source of power is rendered operative in the manner heretofore described by depressing the foot treadle 39 to rotate the main drive shaft 27 at a high rate of speed. As the end of the run is neared the primary source of power is rendered inoperative by elevating the foot treadle and the machine starts to slow down or coast to a stop. At or about the time the needle 22 starts down to complete the second last stitch, the operator moves the knee treadle 93 to the right against the action of the tension spring 94 thus rotating the treadle shaft 86 counter-clockwise as viewed in Fig. 8, until a member (not shown) on the block 88 engages a stop 95 on the bearing 87. As the treadle shaft 86 is thus rotated the rods 81 and 137 are rotated accordingly. During the first part of the rotation of the rod 81 the latch 80 engages the rod 79 and forces it, the compression spring 75 and the rod 70 upwardly as shown in Fig. 9. As the rod 70 is thus forced upwardly the roller 68 carried thereby engages the offset portion of the lever 59 and rotates it and the inner ratchet disk 53 counter-clockwise as viewed in Figs. 1 and 3. As the inner ratchet disk 53 is thus rotated the inclined teeth thereon ride upwardly on the inclined teeth on the stationary outer ratchet disk 54 with the result the inner ratchet disk 53 and the auxiliary power pulley 41 are forced along the bearing bushing 31 until the clutch cones 47 and 48 are forced into frictional engagement as shown in Fig. 7 at which time the auxiliary source of power is rendered operative to continue the rotation of the main drive shaft 27 but at a slower rate of speed. As the lever 59 is thus rotated, the segment 62 is carried upwardly and the pawl 64 in engaging one of the teeth thereon serves to lock the auxiliary source of power in operative position as shown in Fig. 4. The continued rotation of the rod 81 carries the latch 80 upwardly beyond the end of the rod 79, this being permitted by the yield in the compression spring 75. As the latch 80 thus passes upwardly, the rod 79, the compression spring 75 and the rod 70 drop by gravity to their normal position of rest but the auxiliary source of power remains locked in its operative position by the pawl 64 as shown in Fig. 5.

As the rod 137 rotates in response to the rotation of the treadle shaft 86 the rod 135 and the connecting link 133 are pulled downwardly but the amount of free or lost motion in the link 133 is such that the L-shaped lever 125 remains unaffected, as shown in Fig. 9, until the auxiliary source of power has been locked in operative position. The continued rotation of the rod 137, however, rotates the L-shaped rocker arm 125 about its pivot pin 126 and carries the trip latch 124 upwardly thus releasing the main rocker arm 106 by folding the latch lever 116 upwardly. As the trip latch 124 continues upwardly after releasing the main rocker arm 106, the latch lever 116 is instantly restored to its normal position by the compression spring 119. After the main rocker arm 106 is thus released the knee treadle 93 is permitted to be restored to its normal position by the tension spring 94, and as it returns to its normal position the rods 81 and 137 rotate clockwise as they return to their normal position. As the rod 81 returns to its normal position the latch 79 folds, as shown in Fig. 10, and is carried downwardly beneath the rod 79 where it

returns to its normal straight position. As the rod 137 returns to its normal position, the trip latch 124 folds and is carried downwardly beneath the latch lever 116 where it too is permitted to return to its normal position.

In the present embodiment of the invention, the centrally disposed cam 97 is so positioned on the face cam disk 29 that the peak of the high segment 98 is positioned immediately in front of the stud 107 on the main rocker arm 106 as the shaft 27 starts a cycle of operation to carry the needle 22 down and then up to complete a single stitch, and the length of the concentric cam segment 99 is such that by the time the main rocker arm 106 is released in response to a movement of the knee treadle 93 at or about the beginning of the second last stitch a portion thereof is in front of the shaft 105 as shown in Fig. 12. Under these conditions the main rocker arm 106, after being released, is rotated in a counter-clockwise direction by the springs 108 and 109 until the stud 105 is pressed into firm frictional engagement with the concentric cam segment 99 and so applies a braking action which reduces the speed of the machine but the distance the main rocker arm is so rotated is slight and the mechanism controlled thereby other than the braking action on the cam segment 99 remains unaffected. After the stud 105 has been thus pressed into engagement with the concentric cam segment 99 to apply its braking action on the machine the main rocker arm 106 remains stationary until the peak of the high segment 98 is carried around in front of the stud 105 at the end of a cycle of operation at which time the first stitch is completed. Then as the shaft 27 starts the second cycle of operation to complete the next succeeding stitch the main rocker arm 106 starts to rotate counter-clockwise as the stud 105 is maintained in contact with the centrally disposed cam as shown in Fig. 13. The rotation of the main rocker arm 106 counter-clockwise continues until the rise leading to the peak of the high segment 98 is rotated in front of the stud 105 at which time the main rocker arm 106 is rotated clockwise until the peak of the high segment 98 is again rotated in front of the stud 105 at the end of the second cycle of operation, as shown in Fig. 14. As the rise leading to the peak of the high segment 98 is rotated in front of the stud 105 the cam latch 101 is swung outwardly about its pivotal connection to permit the stud 145 to pass out of the cam race 103 and after the stud 105 passes out of the cam race 103 the cam latch 101 is restored to its normal bridged position. During this rotation of the main rocker arm 106, the stud 145 rides in the slot 144 in the rear end of the brake carrying rocker arm 141 thus preventing the slight spaced relationship between the brake shoe 143 and the periphery of the face cam disk 29 from being disturbed.

When the main rocker arm 106 is rotated counter-clockwise the outer end of the lever 165 is carried from beneath the shoulder 164 on the bottom of the parrot lever 158 at which time the leaf spring 166 forces the lever 165 upwardly in front of the shoulder 164 as shown in Fig. 13. Then as the main rocker arm 106 is rotated in a clockwise direction as the peak of the high segment 98 is rotated in front of the stud 105 at the end of the second cycle of operation the lever 165 is carried back. As the lever 165 starts back it first engages the shoulder 164 and rocks the parrot lever 158 about its pivotal connection to carry

the beak of the parrot lever 158 from above the plunger 151, thus releasing it. As the lever 165 continues to move back the guide lip 167 engages the tapered face of the wedge block 168 and forces the outer end of the lever 165 downwardly to its normal position beneath the shoulder 164 on the parrot lever 158. Also, as the main rocker arm 106 is thus rotated clockwise the latch lever 117 is carried back almost to the point where it would be engaged by the latch lever 116.

As the plunger 151 is thus released it and the trunnions 149 and 155 carried thereby move upwardly under the influence of the compression spring 157.

As the trunnion 149 moves upwardly it carries the rod 148 upwardly with it and thus rotates the rocker arm 146 clockwise as viewed in Fig. 15. As the rocker arm 146 is thus rotated it, in turn, rotates the brake carrying rocker arm 141 clockwise and thus causes the brake shoe 143 to be carried into frictional engagement with the periphery of the face cam 29, and since the distance from the pivot pin 142 on which the brake carrying rocker arm 141 to the rear of the arm is considerably longer than the distance from the pivot pin 142 to the front end of the arm the brake shoe 143 is forced into firm frictional engagement with the periphery of the face cam 29 in response to a relatively small force exerted on the rear end of the arm. As the brake shoe 143 is thus engaged the main rocker arm 106 is carried back the additional slight distance necessary to permit the latch 116 engage the block 117 at which time the main rocker arm 106 is so positioned that the stud 105 is out of frictional engagement with the cam elements on the face cam 29, this slight additional movement of the main rocker arm 106 being due to the fact that the face cam 29 in rotating counter-clockwise exerts a thrust on the brake shoe 143 which is mounted forward of a vertical line through the axis of rotation of the face cam 29.

As the trunnion 155 moves upwardly it carries the pawl 64 out of engagement with the teeth on the segment 62 at which time the offset lever 59 and the inner ratchet disk 53 are rotated clockwise by the spring 61 until the inclined teeth 51 on the oppositely disposed faces of the ratchet disks 53 and 54 are restored to their normal full engagement. As the inclined teeth 51 are thus carried into full engagement the inner ratchet disk 53 moves outwardly along the bearing bushing 31 and as it so moves the compression 49 acts to force the auxiliary power pulley 41 outwardly along the bearing bushing thus effecting a separation of the clutch cones 47 and 48 to render the auxiliary source of power inoperative at the end of the second stitch.

Since the auxiliary source of power is adapted and arranged to rotate the main drive shaft 27 at a much slower rate of speed than the primary source of power it, in effect, acts as a brake on the main drive shaft when it is first rendered operative. Also, since the stud 105 is pressed into firm frictional engagement with the cam elements on the face cam 29 when the main rocker arm 106 is released, it too acts as a brake on the main drive shaft 27 and since power is supplied through a transmission clutch the speed at which the shaft rotates gradually decreases. Consequently, when the main brake is rendered operative and the auxiliary source of power is rendered inoperative at the end of the second stitch, the machine is brought to rest without

any great amount of strain on the delicately constructed parts.

From the above it is obvious that if, when the main rocker arm 106 is released, the stud 105 engages the centrally disposed cam 97 rather than the concentric cam segment 99 the mechanism will operate to complete but a single stitch. Also, it is obvious that by increasing the length of the concentric cam segment 99 and/or altering the centrally disposed cam 97, any desired number of stitches may be automatically completed by the auxiliary source of power.

In still further accordance with the present invention, means are provided for resetting the mechanism and for rendering the presser foot 23 inoperative after the main drive shaft 27 has been brought to rest in the desired final position, and to this end the presser foot rocker arm 25 is pivotally connected to a connecting rod 171 which extends downwardly through a compression spring 172 and through an opening in the top of the table 10. The compression spring 172 rests on an apertured disk 173 carried by the top of the table 10, and at its upper end bears against a collar 174 secured to the connecting rod 171 at the central portion thereof. The connecting rod 171 is connected at its lower end to one end of a chain 175 which is trained over a pair of pulleys 176 and 177, the pulley 176 being rotatably mounted on a stud 178 carried by a bracket 179 which is secured to the underneath side of the top of the table 10, and the pulley 177 being rotatably mounted on a stud 181 carried by a bracket 182 which is also secured to the underneath side of the top of the table 10. At its other end the chain 175 is secured to a similar chain 183 at the central portion thereof. At its upper end the chain 183 is secured to a rod 184 carried by the plunger 151 and at its lower end it is connected to a rocker arm 185 at the outer end thereof. The rocker arm 185 is pivotally mounted on a stud 186 carried by a bracket 187 which extends downwardly from the rear bearing 77. At its inner end the rocker arm 185 is positioned over a second rocker arm 188 pivotally mounted between its ends on a stud 189 carried by a bracket 191 secured to the underneath side of the top of the table 10. The second rocker arm 188 at its other end is pivotally secured to an adjustable rod 192 at the upper end thereof and the rod at its lower end is connected to a foot treadle 193. To reset the mechanism and to render the presser foot 23 inoperative the foot treadle 193 is depressed thus rotating the rocker arms 188 and 185 counter-clockwise as viewed in Fig. 1. As the rocker arm 185 is thus rotated the plunger 151 is pulled downwardly in the cylinder 154 against the action of the spring 157 and the rod 171 is pulled downwardly against the action of the compression 172. As the plunger 151 is pulled downwardly against the action of the compression spring 157, the parrot lever 158 is rotated about its pivotal connection by the hairpin spring 163 and the beak of the parrot lever 158 is returned to its normal position over the top of the plunger 151. As the rod 171 is thus pulled downwardly against the action of the compression spring 172 the rocker arm 25 is rotated counter-clockwise as viewed in Fig. 1, and the presser foot 23 is raised to its inoperative position. When the presser foot is released, the compression spring 172 acts to rotate the rocker arm 25 clockwise to restore the presser foot to its down or operative position, and

in so doing a small amount of slack is created in that portion of the chain leading from the rod 184, but when the plunger 151 is again released, this slack is taken up so that the plunger 5 151 may be again returned to its downward locked position when the foot treadle 193 is again depressed.

It is to be understood that in the present embodiment of this invention, the mechanism employed was so designed that it could be mounted on a standard stitching machine with but few changes in the machine, and so that the machine could be run, when desired, in the ordinary manner. It is obvious, however, that in the event 10 it was desired to stop the rotation of the shaft after the end of every run in accordance with the principles of the present invention, many changes and improvements could be made which would simplify the operation. For example, the mechanism could be so designed that when the primary source of power was rendered inoperative the auxiliary source of power would automatically be rendered operative. Also mechanism could be employed which, when pressed into action, would 15 automatically release the main brake shoe 143 and the presser foot 23 the instant the rotation of the main drive shaft was stopped. In addition many other changes and modifications would readily suggest themselves to anyone skilled in the art, all of which however, would embody the 20 principles of the present invention.

Having thus described my invention, I claim:

1. In a stitching machine, the combination of a main drive shaft, a primary source of power adapted to rotate the shaft at a high rate of speed, an auxiliary source of power adapted to continue the rotation of the shaft, and means for applying a braking action on said shaft while it is being rotated by the auxiliary source of power to gradually bring it to rest in a final desired 25 position.

2. In a stitching machine, the combination of a main drive shaft, a primary source of power adapted to rotate the shaft at a high rate of speed, an auxiliary source of power adapted to 30 continue the rotation of the shaft, and means for applying a plurality of braking forces on said shaft while it is being rotated by the auxiliary source of power to bring it to rest in a final desired position.

3. In a stitching machine, the combination of a main drive shaft, a primary source of power adapted to rotate the shaft at a high rate of speed, an auxiliary source of power adapted to 35 continue the rotation of the shaft after the primary source of power has been rendered inoperative, means for gradually decreasing the speed of the shaft while it is being rotated by said auxiliary source of power, and means for rendering said auxiliary source of power inoperative when the shaft has been rotated thereby to a final desired position.

4. In a stitching machine, the combination of a main drive shaft, a primary source of power adapted to rotate the shaft at a high rate of speed, an auxiliary source of power adapted to 40 continue the rotation of the shaft at a slower rate of speed, means for retarding the rotation of the shaft while it is being rotated by the auxiliary source of power, a main brake for said shaft, and means for automatically rendering said auxiliary source of power inoperative and for rendering 45 said main brake operative to gradually bring the shaft to rest when it has been rotated to a final desired position.

5. In a stitching machine, the combination of a main drive shaft, a primary source of power for rotating the shaft at a high rate of speed, an auxiliary source of power for continuing the rotation of the shaft, a main brake for the shaft, and means for gradually decreasing the speed of said shaft during the rotation thereof by the auxiliary source of power and for rendering the main brake operative and the auxiliary source of power inoperative to gradually bring the shaft to rest when it has been rotated thereby to a final desired position.

6. In a stitching machine, the combination of a main drive shaft, a primary source of power for rotating the shaft at a high rate of speed, an auxiliary source of power for continuing the rotation of the shaft, means for locking said auxiliary source of power in operative position, means for gradually decreasing the speed of the shaft while it is being rotated by the auxiliary source of power, and means for rendering said auxiliary source of power inoperative when the shaft has been rotated thereby to a final desired position.

7. In a stitching machine, the combination of a main drive shaft, a primary source of power for rotating the shaft at a high rate of speed, an auxiliary source of power for continuing the rotation of the shaft, means for locking the auxiliary source of power in operative position, and means for gradually decreasing the speed of said shaft while it is being rotated by the auxiliary source of power, and for automatically rendering the auxiliary source of power inoperative when the shaft has been rotated thereby to a final desired position.

8. In a stitching machine, the combination of a main drive shaft, a primary source of power for rotating the shaft at a high rate of speed, an auxiliary source of power for rotating the shaft, a main brake for the shaft, means for locking the auxiliary source of power in operative position, and means for gradually decreasing the speed of said shaft while it is being rotated by the auxiliary source of power and for automatically rendering the main brake active and the auxiliary source of power inoperative to gradually bring the shaft to rest when it has been rotated thereby to a final desired position.

9. In a stitching machine, the combination of a main drive shaft, a primary source of power for rotating the shaft at a high rate of speed, an auxiliary source of power for continuing the rotation of the shaft, means for gradually decreasing the speed of the shaft while it is being rotated by the auxiliary source of power, and means including a cam element for rendering the auxiliary source of power inoperative when the shaft has been rotated thereby to a final desired position.

10. In a stitching machine, the combination of a main drive shaft, a primary source of power for rotating the shaft at a high rate of speed, an auxiliary source of power for continuing the rotation of the shaft, and means including a cam element for gradually decreasing the speed of the shaft while it is being rotated by the auxiliary source of power and for automatically rendering the auxiliary source of power inoperative when the shaft has been rotated thereby to a final desired position.

11. In a stitching machine, the combination of a main drive shaft, a primary source of power for rotating the shaft at a high rate of speed, an auxiliary source of power for rotating the shaft at a slower rate of speed, a main brake, and means including a cam element for automatically ren-

dering the brake active and the auxiliary source of power inoperative to gradually bring the shaft to rest when it has been rotated thereby to a final desired position.

12. In a stitching machine, the combination of a main drive shaft, a primary source of power for rotating the shaft at a high rate of speed, an auxiliary source of power for rotating the shaft at a slower rate of speed, a main brake, and means including a cam element for gradually decreasing the speed of the shaft while it is being rotated by the auxiliary source of power and for automatically rendering the main brake active and the auxiliary source of power inoperative to gradually bring the main drive shaft to rest when it has been rotated thereby to a final desired position.

13. In a stitching machine, the combination of a main drive shaft, a primary source of power for rotating the shaft at a high rate of speed, an auxiliary source of power for continuing the rotation of the shaft, means for gradually decreasing the speed of the shaft while it is being rotated by the auxiliary source of power, a treadle, and means responsive to the movement of the treadle for automatically rendering the auxiliary source of power inoperative when the shaft has been rotated thereby to a final desired position.

14. In a stitching machine, the combination of a main drive shaft, a primary source of power for rotating the shaft at a high rate of speed, an auxiliary source of power for continuing the rotation of the shaft, a treadle, and means responsive to the movement of the treadle for gradually decreasing the speed of the shaft while it is being rotated by the auxiliary source of power and for rendering the auxiliary source of power inoperative when the shaft has been rotated thereby to a final desired position.

15. In a stitching machine, the combination of a main drive shaft, a primary source of power for rotating the shaft at a high rate of speed, an auxiliary source of power for continuing the rotation of the shaft at a slower rate of speed, means for decreasing the speed of the shaft while it is being rotated by the auxiliary source of power, a main brake for the shaft, a treadle, and means responsive to the movement of the treadle for automatically rendering the main brake operative and the auxiliary source of power inoperative to gradually bring the shaft to rest when it is rotated thereby to a final desired position.

16. In a stitching machine, the combination of a main drive shaft, a primary source of power for rotating the shaft at a high rate of speed, an auxiliary source of power for continuing the rotation of the shaft, a main brake for the shaft, a treadle, and means responsive to the movement of the treadle for gradually decreasing the speed of the shaft while it is being rotated by the auxiliary source of power and for automatically rendering the main brake operative and the auxiliary source of power inoperative to gradually bring the shaft to rest when it has been rotated thereby to a final desired position.

17. In a stitching machine, the combination of a main drive shaft, a primary source of power for rotating the shaft at a high rate of speed, an auxiliary source of power for continuing the rotation of the shaft, a face cam fixedly mounted on the shaft and means controlled by the face cam for gradually decreasing the speed of the shaft while it is being rotated by the auxiliary source of power and for automatically rendering the auxiliary source of power inoperative when

the shaft has been rotated thereby to a final desired position.

18. In a stitching machine, the combination of a main drive shaft, a primary source of power, an auxiliary source of power, a plurality of treadles, means responsive to a movement of one of said treadles for rendering said primary source of power operative to rotate said shaft at a high rate of speed, and means responsive to a movement of another of said treadles for rendering the auxiliary source of power operative to continue the rotation of the shaft at a slower rate of speed until the shaft has been rotated thereby to a final desired position.

19. In a stitching machine, the combination of a main drive shaft, a primary source of power, an auxiliary source of power, a plurality of treadles, means responsive to a movement of one of said treadles for rendering the primary source of power operative to rotate the shaft at a high rate of speed, and means responsive to the movement of another of said treadles for locking the auxiliary source of power in operative position to continue the rotation of the shaft at a slower rate of speed and for rendering active mechanism which automatically renders the auxiliary source of power inoperative when the shaft has been rotated thereby to a final desired position.

20. In a stitching machine, the combination of a main drive shaft, a primary source of power, an auxiliary source of power, a plurality of treadles, means responsive to a movement of one of said treadles for rendering the primary source of power operative to rotate the shaft at a high rate of speed and means responsive to the movement of another of said treadles for locking the auxiliary source of power in operative position to continue the rotation of the shaft at a slower rate of speed and for rendering active mechanism which applies a braking action on the shaft and which renders the auxiliary source of power inoperative when the shaft has been rotated thereby to a final desired position.

21. In a stitching machine, the combination of a main drive shaft, a primary source of power, an auxiliary source of power, a main brake for the shaft, a plurality of treadles, means responsive to a movement of one of said treadles for rendering the primary source of power operative to rotate the shaft at a high rate of speed and means responsive to a movement of another of said treadles for rendering the auxiliary source of power operative to continue the rotation of the shaft at a slower rate of speed and for rendering active mechanism which automatically renders the main brake operative and the auxiliary source of power inoperative when the shaft has been rotated thereby to a final desired position.

22. In a stitching machine, the combination of a main drive shaft, a primary source of power, an auxiliary source of power, a main brake for the shaft, a plurality of treadles, means responsive to a movement of one of said treadles for rendering the primary source of power operative to rotate the shaft at a high rate of speed, means responsive to a movement of another of said treadles for rendering the auxiliary source of power operative to continue the rotation of the shaft at a slower rate of speed and for rendering active mechanism which applies a braking action on the shaft and which automatically renders the main brake operative and the auxiliary source of power inoperative when the shaft has been rotated thereby to a final desired position.

position, and means responsive to a movement of still another treadle for releasing said main brake.

23. In a stitching machine, the combination of 5 a main drive shaft, a primary source of power, an auxiliary source of power, a main brake for the shaft, a presser foot, a plurality of treadles, means responsive to a movement of one of said treadles for rendering the primary source of 10 power operative to rotate the shaft at a high rate of speed, means responsive to a movement of another of said treadles for rendering the auxiliary source of power operative to continue the rotation of the shaft at a slower rate of speed 15 and for rendering active mechanism which applies a braking action on the shaft and which automatically renders the main brake operative and the auxiliary source of power inoperative when the shaft has been rotated thereby to a 20 final desired position, and means responsive to a movement of still another treadle for releasing the main brake and for rendering the presser foot inoperative.

24. In a stitching machine, the combination 25 of a main drive shaft, a primary source of power for rotating the shaft, means for rendering the primary source of power operative for a desired interval and for thereafter rendering it inoperative, an auxiliary source of power for continuing 30 the rotation of the shaft, means for rendering the auxiliary source of power operative any time after said primary source of power is rendered inoperative, and means for gradually decreasing

the speed of the shaft while it is being rotated by the auxiliary source of power and for rendering the auxiliary source of power inoperative when the shaft has been rotated thereby to a final desired position. 5

25. In a stitching machine, the combination of a main drive shaft, a primary source of power for rotating the shaft, means for rendering said primary source of power operative for a desired interval and for thereafter rendering it inoperative, 10 an auxiliary source of power for continuing the rotation of the shaft, means for rendering said auxiliary source of power operative any time after said primary source of power has been rendered inoperative, a brake for the shaft, and means for gradually decreasing the speed of the 15 shaft while it is being rotated by the auxiliary source of power, for rendering the brake operative and for rendering the auxiliary source of power inoperative when the shaft has been rotated thereby to a final desired position. 20

26. In a stitching machine, the combination of a primary source of power adapted to rotate the shaft at a high rate of speed, an auxiliary source of power, means for rendering the auxiliary source of power operative to automatically complete a predetermined number of machine cycles of operation after the primary source of power has been rendered inoperative, and means operable during said predetermined number of 25 machine cycles of operation to gradually bring the shaft to rest in a desired position. 30

J. WILLIAM BEDARD.
